UNITED STATES PATENT OFFICE.

EDWARD N. UNRUH, JR., OF CORSICANA, TEXAS.

CABLE-SPOOLING DEVICE.

Application filed December 23, 1926. Serial No. 156,722.

This invention relates to new and useful improvements in devices for use in the spooling or unspooling of cable upon or from a cable spool, and has for its primary object to provide a machine wherein the spool may be rapidly associated with or removed from the machine, and this without requiring the entire dismantling of the machine, and no unusual skilled labor upon the part of the operator.

10 A further and most important object is to provide means whereby the tension of the cable may be regulated during the removal of the cable from the spool.

15 Yet another object is to provide a machine of this character that is extremely novel, simple, and efficient in operation, the same embodying but few parts and these so correlated as to reduce the possibility of disarrangement to a minimum.

20 With the foregoing and other objects in view as the nature of the invention will be better understood, the same comprises the novel form, combination and arrangement of parts hereinafter more fully described, shown in the accompanying drawings and claimed.

25 In the accompanying drawings wherein like numerals indicate corresponding parts throughout the several views:

30 Figure 1 is a side elevation of a cable spooling machine constructed in accordance with the present invention.

Figure 2 is an end elevation thereof.

35 Figure 3 is an enlarged fragmentary elevation of the braking mechanism whereby the tension on the cable may be controlled when removing the cable from the spool.

Figure 4 is a somewhat similar view in longitudinal cross section, and

40 Figure 5 is a perspective of one of the spool engaging cones.

Now having particular reference to the drawings, my novel device consists of a pair of spaced vertical standards 5 and 6. The 45 upper end of the standard 5 is equipped with a sectional shaft bearing 7, while the upper end of the standard 6 terminates in a pair of vertically extending spaced arms 8-8, the upper ends of which are also equipped with 50 sectional shaft bearings 9-9. Arranged within the bearings 9-9 of the arms 8-8 is the outer end of a hollow shaft 10, upon the inner end of which is disposed a spool engaging cone 11. This cone 11 may be of any pre-determined size and is formed centrally with a horizontal bore 12, the outer end of which

is of enlarged diameter for receiving the inner end of the hollow shaft 10. The exterior surface of this shaft 10 at its inner end is horizontally channeled as at 13, while the enlarged area of the cone bore is also formed with a horizontal channel 14 registering with the channel 13 in the shaft 10 so as to receive a locking key 15.

55 Mounted within the bearing 7 at the upper end of the standard 5 is a similar hollow shaft 16 to the inner end of which is fixed a spool engaging cone 17 identical in construction to the cone 11 and secured to the shaft 16 in a manner similar to the securing of said cone 11 to its shaft 10.

60 Each of the cones is formed with longitudinally extending spaced ribs 18, somewhat sharpened at their edges for obviously cutting into the material forming the cable spool 75 A disclosed in dotted lines in Figure 1.

65 The spool engaging cones 11 and 17 are normally in spaced relation, a distance slightly less than the width of the spool A, it being obvious that when it is desired to arrange a 80 spool between said cones, it is necessary that one of the standards 5 or 6 be moved to such a position as to permit the spool to be arranged upon one of the cones. This standard is then positioned so that its cone will engage with 85 in the opposite end of the spool so as to firmly secure the same between the cones.

70 After the spool A has been properly arranged between the cones 11 and 17 there is disposed through the shafts 10 and 16 an 90 elongated bar 19 headed at one end as at 20 and threaded at its opposite end as at 21, see Figures 1 and 4. After this bar has been extended through the hollow shaft, nuts 22 are threaded upon the threaded end thereof 95 so as to prevent separation of the standards 5 and 6 and to securely lock in horizontal alignment the cone carrying shafts 10 and 16.

75 Keyed to the shaft 10 intermediate the arms 8-8 of the standard 6 is a brake drum 23 100 circumferentially flanged at its opposite edges as at 24-24. Arranged substantially entirely around this drum 23 is a metallic brake band 25 provided on its inner face with a 105 brake lining 26. One end of the band 25 is rolled to form a bearing 27 for a pin 28, the ends of which extend through said bearing and to which are attached eye bolts 29-29, the eyes thereof encircling a pin 30 secured at its opposite ends in registering 110 openings provided therefor in the lower end of the arms 8-8 of the standard 6. The op-

posite end of this band 25 is also rolled to form a bearing 31 within which is a pin 32, the center of this bearing being slotted so as to permit of the pivotal attachment of the eyed 5 end 33 of an elongated pin 34 to said pin 32. Rotatably mounted upon the pin 30 between the eye bolts 29—29 is a block 35 to which is secured an outwardly extending hand lever 36 of circular shape in cross section and over 10 which the eyed outer end 37 of the elongated pin 34 is disposed. The inner end of this hand lever 36 is of enlarged diameter as at 38, see Figure 2 so as to limit the inward movement of the pin 34 thereon. Obviously 15 by forcing downwardly upon the lever 36, the band 25 is tightened upon the drum 23 for braking the rotation of the shaft 10 and 16 as well as the spool A.

Associated with the shaft 16 is a suitable 20 sprocket wheel 38 over which may be trained an endless driven sprocket chain so as to facilitate the rotation of the spool A during the winding of cable thereon.

In view of the foregoing description when 25 considered in conjunction with the accompanying drawings it will at once be apparent that I have provided a highly novel, simple and efficient cable spooling machine that is well adapted for all the purposes heretofore 30 designated, even though I have herein shown and described the invention as consisting of

certain detail structural elements, it is nevertheless to be understood that minor changes may be made therein without affecting the spirit and scope of the appended claim.

35

Having thus described the invention, what I claim is:—

In a cable spool machine of the class described, a pair of spaced standards, horizontally aligned hollow shafts journaled at their outer ends within the respective standards at the upper ends thereof, a pair of opposed spool supporting cones, the outer larger end of each cone being provided with an enlarged socket to receive the inner end of the respective hollow shaft, the adjacent faces of the inner end of each hollow shaft and the socket of the respective cone being provided with co-operating channels, a key insertable in said channels to positively lock the cones on the inner ends of the shaft, longitudinally extending ribs formed on the outer face of each cone for forcible engagement with the bore of the spool at the respective ends thereof, an elongated bolt extending longitudinally through the hollow shafts and the cones for interconnecting the standards, and a driving member arranged on one of the hollow shafts for effecting the rotation of the spool supported on the cones.

55

In testimony whereof I affix my signature.

EDWARD N. UNRUH, Jr.
